Alfred C. Kather, San Francisco, Calif.

Application April 6, 1951, Serial No. 14,724

Term of patent 3½ years

(Cl. D85—8)

To all whom it may concern:

Be it known that I, Alfred C. Kather, a citizen of the United States, residing at 365 Golden Gate, in the county of San Francisco, city of San Francisco, and State of California, have invented a new, original, and ornamental Design for a Combined Cigarette Stand and Holder, of which the following is a specification, reference being had to the accompanying drawing, forming part thereof.

Fig. 1 is a perspective view of a combined cigarette stand and holder, showing my new design.

Fig. 2 is a top view thereof.

I claim:

The ornamental design for a combined cigarette stand and holder, as shown.

ALFRED C. KATHER.
